UNITED STATES PATENT OFFICE.

ALBERT W. SMITH AND WILLIAM J. DUVALL, OF ST. LOUIS, MISSOURI.

BED.

Application filed October 18, 1922. Serial No. 595,260.

To all whom it may concern:

Be it known that we, ALBERT W. SMITH and WILLIAM J. DUVALL, citizens of the United States, residing at the city of St. Louis, in the State of Missouri, have invented certain new and useful Improvements in Beds, of which the following is a specification.

The object of this invention is to provide a bed adapted for use as what is known as a wall-bed or an in-a-wall-bed, which shall be of the simplest form of construction and devoid of the cumbersome and special head and lifting parts heretofore common in such constructions. Such beds now on the market are usually provided with a separate head-piece for the lifting and balancing members, which extra head-piece projects to the rear of the head proper and takes up a material amount of room, which is an extremely undesirable feature in a wall-bed or similar structure. The said extra projecting part is a source of large expense, not only because of the material and labor embodied in it, but also because of forcing the provision in the building of an apartment-house or the like, in which the same is to be used, of closets or receptacles of large dimensions, in order to receive a wall-bed having such a rear projection.

Among the merits of the present invention may be mentioned the inclusion between its head and foot of the necessary lifting and balancing devices and means for holding the mattress from slipping, whereby less room will be required within the wall of a building to receive the same when folded to be stowed out of use. This is of the greatest importance, because it permits greater use by an architect and builder of the available land area and it allows the construction of apartments or the like on lots of land that would otherwise be too small or it enables the provision in such buildings of larger and more commodious rooms.

Moreover, this invention can be attached to practically any standard or stock bed, and the same thereby be converted into a wall-bed or the like, which saves much in the way of special parts, special manufacture, machinery, and equipment.

While this bed is primarily intended as a wall-bed, yet other uses are possible.

In the accompanying drawings forming part of this specification, in which like num-

bers of reference denote like parts wherever they occur,

Figure 1 is a side elevation of the bed extended;

Figure 2 is a side elevation of the same folded and attached to a door or other movable wall-piece; and

Figure 3 is a vertical transverse sectional view on the irregular line 3—3 of Figure 1.

When used as a wall-bed the head 1 of the bed may be attached in any desired manner to the door 2. When temporarily not in use, the bed will be caused in any desired manner to be withdrawn into the alcove, 70 closet, or recess provided for that purpose.

The foot 3 of the bed is preferably pivoted at 4 to the main frame 5. The box-spring 6 and the mattress 7 rest upon bed-bottom frame 5. This bed is not restricted to the use of a box-spring, but may be variously equipped.

Preferably a projection 8, which may be either one long piece or a plurality of parts, limits the travel of the box-spring 6 and 80 the mattress 7 or a substitute for the same in the direction toward the head 1 which results when the parts are moved to the position shown in Figure 2 with the spring 6 or the mattress in its place resting thereon, 85 and, also, limits their downward movement.

The frame 5 is supported upon the floor when the bed is open, as shown in Figure 1, by the foot 3 resting on the floor, the rods 9 and 10, pivoted in the plate 4, swinging 90 from the position shown in Figure 2 to that shown in Figure 1, for the purpose of allowing foot 3 to occupy the position shown in Figure 1.

At the other end the frame 5 is supported by the frame 11, fixed to the head 1, which in general extends from one side of the bed to the other and is pivoted at 12 to the side members of frame 5 on each side. Indirectly frame 5 is supported by the head 1, 100 which rests upon the floor, but the connection therebetween is by means of the frame 11, springs 13, rod or plate 14, and links 15, which by means of hooks 16 and 17 on their ends are pivoted to plate 14 and the end 105 member 18 of frame 5.

Extending above the said end member 18 and for the purpose of holding the mattress 7 or the like and the bedclothing from slipping when the bed is closed to the position shown in Figure 2, frame 19 is provided, composed of a plurality of curved

rods 20. To the upper part or rod 21 of frame 19, pivoted at 29 to end projection 8, are attached by hooks or eyelets 22 a plurality of rods 23, which are telescoped by holes 5 low rods 24, and are adapted to move longitudinally therein, ascending when the bed is extended, as shown in Figure 1, and descending when the same is closed to the position shown in Figure 2. The rods 23 10 assist in holding the bedclothing and mattress 7 in proper position.

It will be observed that the hooks 25 and the hooks 26, by which springs 13 are attached, respectively, to rod or plate 27 15 forming part of frame 11 and rod or plate 14, are pivotal connections between the said frame 11 and the frame 28, of which rod or plate 14 forms a part. Frame 28 is pivoted at 30 to head 1, similarly the hooks 17 on 20 links 15 form another pivotal connection for frame 28, hooks 16 forming a pivotal connection between the end member 18, connecting the end projections 8 of the frame 5, and the links 15. Furthermore, frame 11 25 is pivoted at 12 to the sides of frame 5.

Thus the bed bottom 5 is adapted to rotate on pivot points 12 on both sides of frame 11, the degree of its said rotation being indicated by the change of position depicted 30 in Figure 2 as compared to the position shown in Figure 1.

By this construction it is possible so to arrange springs 13 and the various pivot points just mentioned that a slight upward 35 impulse conveyed to the foot 3 of the bed will cause the bed to rise to the position shown in Figure 2, because the springs 13 will do the major part of the lifting. The movement forward or backward of the 40 pivotal points at hooks 17 and 26 will provide adjustment that will accommodate any alteration in weight or load or material of manufacture. One of the greatest advantages of this construction is that the springs 45 13 are not under constant tension; nevertheless, whenever it is desired to close the bed they immediately exert their pulling force. In other beds the lifting springs are under constant tension, which necessarily reduces the length of their life, and, also, reduces their resiliency and tends to produce 50 the objectionable feature of the danger that at any time there may be a broken spring.

The feature of the springs 13 not being

under constant tension but being called into 55 action instantly upon the movement of the bed in the direction of the position shown in Figure 2 is due to the shape and position of the frame 11 and the direction of arrangement or location of the springs 13, relative 60 to the angular frame 11, and the location of the pivotal point 26.

It should be understood that while the pivoting of various members herein shown and described is produced by hooks passing 65 through holes in members, yet other modes of pivoting may be practiced, as, for instance, the hooks may be eyes; the hooks herein shown may be placed upon the other members in reverse arrangement from what 70 is herein shown; or other means for pivoting may be used.

This construction is adapted for use in davenets and similar beds or couches.

Having thus described this invention, we 75 hereby reserve the benefit of all changes in form, arrangement, order, or use of parts, as it is evident that many minor changes may be made therein without departing 80 from the spirit of this invention or the scope 85 of the following claim.

We claim:

A bed comprising a stationary head presenting a plurality of hollow rods spaced laterally across its upper portion, a bed bottom pivoted to the said head for movement into a vertical position, a frame composed of a plurality of curved rods arranged between the said stationary head and the pivoted end of the said bed bottom with its lower part pivoted to the said bed bottom, said frame being adapted to move vertically of the said stationary head as the said bed bottom is raised and lowered and being of such curvature as to close over the lower end of the bed bottom in the upended position of the latter, and a plurality of rods slidably engaged within the said hollow rods of the stationary head and connected to the said frame for movement exteriorly 95 of the hollow rods as the said frame is moved downwardly, said rods being adapted when extended from the hollow rods to form continuations of the said hollow rods.

In testimony whereof we hereunto affix our signatures.

ALBERT W. SMITH.
WILLIAM J. DUVALL.
